George Grant Peterson

Chas. H. Luther

ATTORNEY:

UNITED STATES PATENT OFFICE.

GEORGE GRANT PETERSON, OF EAST PROVIDENCE, RHODE ISLAND.

ICE-CREAM CABINET.

Application filed February 23, 1922. Serial No. 538,603.

To all whom it may concern:

Be it known that I, GEORGE GRANT PETERSON, a citizen of the United States, residing at East Providence, in the county of Providence and State of Rhode Island, have invented a new and useful Improvement in Ice-Cream Cabinets, of which the following is a specification.

In the usual construction of ice-cream cabinets there is no provision for taking care of condensation of moisture in the walls and bottom of the cabinet. Such cabinets are usually not properly insulated, consequently the cost for ice is excessive and the cream does not keep well, also there is no drip-pan to take care of excessive moisture from the cabinet.

The object of my invention is to improve the construction of an ice-cream cabinet, whereby all the above objectionable features enumerated are entirely eliminated and a more perfect ice-cream cabinet produced than has heretofore been done.

A further object of my invention is to produce an ice-cream cabinet in which ice-cream may be kept harder and longer and in which the cost for ice is reduced to a minimum.

My invention consists in the peculiar and novel construction of an ice-cream cabinet, said ice-cream cabinet having details of construction, as will be more fully set forth hereinafter and claimed.

Figure 1 is a top plan view of my improved ice-cream cabinet with part of the cover broken away.

Figure 2 is a front view of the cabinet showing one end in section.

Figure 3 is a horizontal sectional view taken on line 3, 3, of Figure 2 and showing the drip-pan in full.

Figure 4 is an enlarged detail vertical sectional view of one end taken on line 4, 4 of Figure 1.

Figure 5 is an enlarged detail horizontal sectional view of part of the bottom of the cabinet, and

Figure 6 is an enlarged detail horizontal sectional view taken through one corner of the cabinet.

In the drawings 7 indicates the body of the cabinet construction as follows: Four wood corner posts 11, 11, which extend down below the bottom and form corner legs 12, 12. An upper wood frame 13 having an inner inclined edge 14 and a continuous

tongue 15 which enters a corresponding continuous groove 16 in the body cover 8, as shown in Figure 2. The front 17, back 18 and end walls 19, 19 are all of the same construction which is as follows, an outer sheathing 20 of sheet metal, a layer of paper 21, a layer of cork 22, a layer of cement 23, a layer of cork 24, a layer of paper 25 and an inner lining 26 of sheet metal which extends up and over the inclined edge 14, as shown in Figure 4. The construction of the bottom 27 is as follows: A lower layer of wood 28, a layer of paper 29, a layer of cork 30, a layer of paper 31, a layer of wood 32, a layer of paper 33, a layer of cork 34, a layer of paper 35 and an inner lining layer 36 of sheet metal, as shown in Figure 5. The cork layer 30 extends outward all around into a groove 37, as shown in Figure 2, in the front, back and end walls. All of the cork used is preferably in the form of strips or bars. The front, back and end walls are further strengthened by strips of metal 38, 38, as shown in broken lines in Figure 2. These strips 38, 38 extend crosswise from the bottom of one corner to the top of the opposite corner, inside of the outer sheathing and are secured at their ends to the corner posts. Slits 39, 39, are formed in the top at the corners, as shown in Figure 1. The corners of the cabinet are still further reinforced by outside metal strengthening members 40, 40, as shown. A drain pipe 41 extends from the inside of the body 7 and connects on the outside with the usual faucet 42, as shown in Figure 2.

The body cover 8 fits over the body 7 as shown and has the usual openings 43, 43 for access to the ice-cream containers 10, 10 and which are closed by the usual individual covers 44, 44.

The drip-pan 9 is shaped to fit around the legs 12, 12 and the bottom 45 is shaped to incline towards the center of the pan and towards one end 46 of the cabinet whereby this end 46 is deeper, as shown in Figures 2 and 3. A drain cock 47 is placed at this end 46, for draining water from the pan.

When in use the ice-cream containers 10, 10 are packed in ice, not shown. Condensed moisture in the walls rising by capillary attraction will come out of the corner slits 39, 39 and flow over the inclined edges 14, 14 and down into the cabinet. Any excess of condensed moisture in the walls and bottom of the cabinet will flow downwards and

drip into the dip-pan 9, from which it may be removed when required, through the drain cock 47. Water is removed from the inside of the cabinet through the drain-pipe 41 and faucet 42, which may be connected to a soil-pipe, if desired.

I do not wish to confine myself to the exact relations of the different elements composing the walls and bottom of my improved ice-cream cabinet, as these could be changed in their relation to each other within the scope of the appended claims.

Having thus described my invention I claim as new:—

- 15 1. An ice-cream cabinet having a bottom, front, back and end walls, a cover, said walls consisting of an outer layer of sheet metal, a layer of paper, a layer of cork, a layer of cement, a layer of cork, a layer of paper, and an inner lining of sheet metal, for the purpose as described.
- 20 2. An ice-cream cabinet having a bottom, front, back and side walls, a cover, said bottom consisting of a layer of wood, a layer of paper, a layer of cork, a layer of paper, a layer of wood, a layer of paper, a layer of cork, a layer of paper, and an inner lining of sheet metal, for the purpose as described.
- 25 3. An ice-cream cabinet having a bottom, front, back and end walls, a cover, said walls consisting of an outer layer of sheet metal, a layer of paper, a layer of cork, a layer of cement, a layer of cork, a layer of paper, and an inner lining of sheet metal, for the purpose as described.
- 30

layer of cement, a layer of cork, a layer of paper, and an inner lining of sheet metal, said bottom consisting of a layer of wood, a layer of paper, a layer of cork, a layer of paper, a layer of wood, a layer of paper, a layer of cork, a layer of paper, and an inner lining of sheet metal, for the purpose as described.

35

4. An ice-cabinet having a bottom, front, back and end walls, a cover, said walls consisting of sheet metal, paper, cork and cement and said bottom consisting of wood, paper, cork and a sheet metal lining and a drip pan under the bottom and secured to the cabinet, for the purpose as described.

40

5. An ice-cream cabinet having corner legs, a bottom, front, back and end walls, cross-wise metal strengthening strips in the walls, corner slits at the top of the walls which have inclined top edges, a cover, said walls consisting of sheet metal, paper, cork and cement, said bottom consisting of wood, paper, cork and sheet metal, a drip pan under the bottom forming a part of the cabinet, shaped to fit around the legs of the cabinet and being deeper at one end, means for drawing water from the cabinet and means for draining water from the drip pan, for the purpose as described.

50

In testimony whereof, I have signed my name to this specification.

GEORGE GRANT PETERSON.
